UNITED STATES PATENT OFFICE.

THOMAS ROBERT KNOWLES, OF WEST BROMWICH, ENGLAND.

MANUFACTURE OF ROLLED WHEELS AND DISKS.

1,306,262.

Specification of Letters Patent. Patented June 10, 1919.

Application filed July 26, 1915. Serial No. 42,102.

To all whom it may concern:

Be it known that I, THOMAS ROBERT KNOWLES, a subject of the King of Great Britain, residing at "Beecholme," Hill Top,

5 West Bromwich, in the county of Stafford, England, engineer, have invented new and useful Improvements in the Manufacture of Rolled Wheels and Disks; and I do hereby declare the following to be a full, clear, and

10 exact description of the same.

This invention comprises improvements in the manufacture of rolled wheels and disks and refers more particularly to rolled car wheels, but may be used for forming blanks

15 for gear wheels and for any other analogous purposes. In apparatus for this purpose it is well known to employ rotary dies to form the two side surfaces of the wheel, the rotary dies being mounted at an angle to each other

20 and having recesses in which a roughly formed boss is engaged to support the bloom during the operation. Usually the axes of the dies are set at an angle of not less than 15° from the straight and the dies are ar-

25 ranged to overlap at the perimeter on the operative side of the axis so as to shape the wheel to the rim, or in some cases to the flange or tire, or instead of such overlapping parts an adjustable rim roller is used.

30 I find that the difficulties encountered in rolling bodies, such as wheels, arise mainly through this large angle of divergence of the dies, which checks the flow of the metal in the operative surfaces of the dies, which

35 should be toward the rim but tends instead, owing to the resistance due to the steep angle, to move the boss of the bloom from the main recesses of the dies. This results in a badly shaped boss, which has hardly been worked

40 upon at all and in a rim which lacks solidity.

The spindles of the dies are both inclined with respect to a straight line drawn through the center of the bloom when between the dies and are arranged so that their axes

45 would meet on the straight line aforesaid at the said central point of the boss of the bloom when in position between the dies.

In accordance with this invention I arrange the rotary dies so that the axes of both 50 the dies have a very slight diversion from the straight, the angle of their diversion being very small, between 1½° and 5°. Thus the operation of rolling is so gradual as to form or resemble a spinning or planishing

55 action.

On the drawings:

Figure 1 is a part sectional elevation of a disk mill according to my invention.

Fig. 2 is a plan thereof.

Fig. 3 is a sectional view to a larger scale 60 showing the dies just coming into operative relation with the bloom.

Fig. 4 is a similar view showing the conclusion of the rolling operation.

Fig. 5 is a transverse section on line 5—5 65 of Fig. 1.

Fig. 6 is a section of a suitable bloom.

Fig. 7 is a similar view of the rolled car wheel.

On these drawings *a b* represent two dies 70 mounted upon spindles *c d*, which are inclined to a straight line *x—y* drawn through the center of the bloom *e* between the dies. The axes of the spindles *c d* would meet on the straight line aforesaid at the central 75 point in the boss of the bloom when in position between the dies, which point is marked *f* at Figs. 2 and 4.

Both dies may be rotated and both may be withdrawn to permit the insertion of the 80 bloom and advanced for the rolling operation. The means for effecting these movements of the dies shown on the drawings will be hereafter described as one suitable arrangement.

At the back of the dies *a b* where they approach each other more closely, see Fig. 4, I arrange a rim roller *g* adapted to bring the desired pressure upon the metal of the bloom, as it expands under the rolling action, so as 90 to compel it to fill the lateral spaces between the dies to form the rim of the disk or wheel.

A bloom *h* Fig. 6 is inserted between the dies *a b* which are both advanced to close upon it so that its boss is held in the accommodating recesses *a¹ b¹* of the dies. The surfaces of the recesses *a¹ b¹* are slightly conical so that in the inclined position of the dies the rear half of each forms a rolling surface for the boss from the center to its periphery, 100 while the front half forms a clearance. The rolling operation upon the heated bloom is then commenced the dies being rotated and gradually advanced to shape the bloom between their surfaces and gradually 105 expand the metal toward the rim roller *g*. The configuration of the dies will of course depend upon the article to be produced; as here shown the dies are suitable for producing a car wheel such as in Fig. 7. In 110

such an article the rim is of greater thickness than the web or disk portion and to enable the spaces a^2 b^2 of the dies to be filled with the metal so as to give the desired 5 solidity to the rim the rim roller g is arranged so as to exert a pressure upon the metal to cause it to expand laterally. By this action and by the gradual nature of the rolling action owing to the slight angle of 10 the rolling die faces a very clean shaping of the metal is effected free from distortion but with great solidity at the boss and rim.

For operating the dies in the example shown on the drawings, the dies are mounted 15 on the substantial spindles c , d before mentioned, mounted in suitable bearings on adjustable carrier plates c' , d' , which are adjustable about a pivot bolt f upon a main bed j . The spindles are rotated by a motor 20 k direct or by gearing from any suitable source of power. The means for rotating the dies forms no part of the invention. For moving the dies axially to permit the bloom e to be inserted between them and to 25 close them onto it and gradually advance them for the rolling operation I prefer to provide the spindles with collars l working behind shoulders m and provided with trunnions n connected by short links o to large 30 bellcranks p mounted at q . The other ends of the bell cranks are connected to a hydraulic or other plunger r .

As here shown the bolsters in which the spindles work together with the more remote bearings and the driving means are movable bodily on the bed plate j .

The use of a hydraulic or other cylinder and ram or plunger for the operation of advancing and retarding the dies is particularly suitable as by means of proper control a very gradual advance can be obtained with a rapid return, which is desirable when the rolling operation is concluded, as continued rolling after the proper shaping is obtained is disadvantageous.

For adjusting the back roller g , which is not driven but rotated by friction with the bloom, I also prefer to employ a hydraulic or other cylinder t mounting the roller in a 50 suitably guided head u on the plunger v , see Fig. 5. If desired I may arrange a guide roller above and below the roller g to assist in centering the bloom, see g' Fig. 5.

The roller g may be adjusted exactly to 55 its work by mounting it on screwed rods w working through tapped worm wheels z driven by a worm 1 on the hand wheel shaft 2, see Figs. 2 and 5.

The advance of the dies should be slight 60 in relation to the revolutions so as to insure the desired gradual rolling or "spinning" action. Without in any way setting an arbitrary limit I believe the advance should not exceed $\frac{1}{2}$ of an inch per die per 65 revolution. It may be preferable to ar-

range for driving the die advancing mechanism at two speeds so that in first roughing down the blank the advance may be more rapid than in the later stages of the operation. As an approximate speed of rotation 70 for the dies I may arrange for 90 revolutions per minute during the roughing down operation and 180 revolutions during the later stages.

If desired the rim roller may be plain instead of formed as shown and a separate tire may be secured on the wheel but the form shown enables the flange to be formed on the wheel at one operation.

The dies may be curved on their contours 80 if desired, to give a dished form to the disk or web of the wheel at one rolling operation. The carrier plates c' , d' on which the main spindles and gear may be mounted may be adjusted about the pivot point f and clamped 85 in the adjusted position to the main bed j . The carrier plates and spindles may thus be set to give the desired small angle between the dies so that the small angle is adjustable within the stated limits, to suit the 90 particular articles being rolled. The adjustment of the carrier plates c' , d' about the pivot bolt f it will be understood, is effected before commencing work and the plates are then locked in the adjusted position on the 95 bed j , such as by bolts at f' , f'' , Fig. 2.

What I claim then is:

1. Apparatus for the manufacture of rolled wheels and the like comprising in combination a pair of rolling dies disposed 100 with their die faces toward each other, said rolling dies being mounted on rotary spindles, the axes of both said spindles diverging at a very slight angle only from a straight line through the center of the bloom, said 105 axes meeting said line at the central point in the mass of the bloom, bearings in which said spindles are mounted, adjustable carriers for said bearings, whereby both said spindles and said rolling dies may be adjusted as to the slight angle of divergence of 110 their axes from said straight line through the center of the bloom, when the bloom is in place between the dies, said carriers being adjustable between $1\frac{1}{2}^{\circ}$ and 5° to suit the 115 work to be operated upon.

2. In roll apparatus for producing rolled wheels, disks and analogous articles by means of rotating inclined surfaces, a pair of rotary dies, the axes of both of said dies 120 having a very slight divergence from a given straight line and meeting on the said straight line at the central point of the boss of the bloom, means for rotating said dies, means for advancing and returning the said 125 dies including power cylinders, and bell cranks intermediate said cylinders and said dies, a rim roller, a power cylinder for actuating said rim roller and keeping the same in operation against the bloom during the 130

rolling action of the dies, means for engaging said rim roller with the power cylinder so as to permit its exact adjustment to the work.

- 5 3. In roll apparatus for producing rolled wheels, disks and analogous articles by means of rotating inclined surfaces, a pair of rotary dies, the axes of both of said dies having a very slight divergence from a given
- 10 straight line and meeting on the said straight line at the central point of the boss of the bloom, means for rotating said dies, means for advancing and returning the said dies including power cylinders, and bell
- 15 cranks intermediate said cylinders and said dies, a rim roller, a power cylinder for actuating said roller and keeping the same in operation against the bloom during the rolling action of the dies, means for engaging
- 20 said rim roller with the power cylinder so as to permit its exact adjustment to the work, said means comprising screwed rods working through tapped worm wheels driven by a worm on a hand operated shaft.
- 25 4. Apparatus for the manufacture of rolled wheels and the like comprising in combination a pair of rolling dies disposed with their die faces toward each other, said rolling dies being mounted on rotary spin-

dles, the axes of both of said spindles diverging at a very slight angle only from a straight line through the center of the bloom, said axes meeting said line at the central point in the mass of the bloom, bearings in which said spindles are mounted, adjustable carriers for said bearings, whereby both of said spindles and said rolling dies may be adjusted as to the slight angle of divergence of their axes from said straight line through the center of the bloom, when the bloom is in place between the dies, said carriers being adjustable between $1\frac{1}{2}^{\circ}$ and 5° to suit the work to be operated upon, and means for advancing and returning said dies including hollow cylinders and bell cranks intermediate said cylinders and said dies, and a rim roller, a cylinder for actuating said roller and for keeping the same in operation against the bloom during the rolling action of the dies.

In testimony whereof, I have signed my name to this specification in the presence of two subscribing witnesses.

THOMAS ROBERT KNOWLES.
